WASHING MACHINE

William Strobridge, Syracuse, N. Y., assignor, by
mesne assignments, to Reconstruction Finance
Corporation, a corporation of the United
States

Application February 13, 1932, Serial No. 592,716
Renewed June 21, 1935

12 Claims. (Cl. 68—18)

This invention relates to washing machines or the like of the drum type, and more particularly to the internal construction thereof.

In the past it has been common practice to employ cylinders of the open type in washing machines of the above character, that is, with no longitudinal partitions; which cylinders have usually been constructed with the periphery sheets perforated throughout their entire circumference to permit of free ingress and egress of the solution contained in the tub in which the cylinder is mounted for rotation. This solution is usually maintained at a low level so that a relatively shallow segmental section of the cylinder lies below the said level. Water flows continuously in and out of this section through the perforated sheets as the cylinder rotates. The washing action of such an open cylinder depends upon the alternate lifting of the batch of wash by means of tumbling-ribs distributed circumferentially upon the interior thereof and the dropping of the lifted batch back into the solution contained in the bottom of the cylinder. Thus, during the operation of such an open type cylinder the batch is progressively submerged in the liquid at the bottom of the cylinder, is spread out therein, permitting penetration of the wash water or other treating liquid, and thereafter submitted to a squeezing action while being lifted by the tumbling-ribs.

In recent years, however, particularly in hotel and institutional laundries where the degree of soiling does not justify a long washing operation, where greater capacities for a given floor space are demanded and where the quality of labor is a factor, there has been introduced a washing cylinder with longitudinal partitions, usually three, forming what is known to the trade as a "Y" pocket-washer. Such cylinders are usually divided by transverse vertical partitions to form anywhere from nine to twenty-four pockets, depending upon the length of the cylinder, and each pocket is provided with a sliding door. Care is taken that these pockets shall not be of such length as to necessitate the use of a door of too large and unwieldy proportion.

By thus dividing the washing cylinder by longitudinal partitions, the drop and squeeze action of the open type cylinder has been largely eliminated in the majority of present "Y" pocket washers except for the longitudinal row of pockets which for the moment happens to be down in contact with the liquid in the tub of the washing machine. Thus, for two-thirds of each revolution of such

a cylinder the load does not come in contact with the solution.

One of the objects of the present invention is to provide a pocket-washer in which an improved washing action is attained. A further object is to provide a pocket-washer of the character described in which efficient washing action will take place not only while the batch of material in a pocket is submerged, but also during its period of travel through the tub space above the liquid level. A further object is to provide a simple and practical means for admitting washing fluid to a pocket during its submergence, removing a portion thereof from contact with a load carried by said pocket during a succeeding portion of a revolution of the cylinder, and later permitting the stored fluid to descend as a spray upon the batch contained in the pocket. A further object is to provide a practical "Y" pocket-washer in which the batch of material contained in any pocket will be successively squeezed together and spread out, both in and out of the washing solution and also be submitted to efficient scrubbing action.

Other objects will be in part obvious and in part pointed out hereinafter.

The invention accordingly consists in the features of construction, combination of elements, and arrangements of parts as will be exemplified in the structure to be hereinafter described and the scope of the application of which will be indicated in the following claims.

In the accompanying drawings in which is shown one of the various possible embodiments of my invention:

Fig. 1 is a front elevation of a portion of a washing machine of the type described, with a part of the tub broken away and with the door in the tub in raised position showing the door of the washing cylinder in registry with the tub opening;

Fig. 2 is a cross-section through tub and cylinder taken on line 2—2 of Fig. 1;

Fig. 3 is an enlarged cross-section similar to Fig. 2 of a portion of the cylinder showing in clearer detail certain features of my invention;

Fig. 4 is a partial section on enlarged scale taken substantially on line 4—4 of Fig. 1; and

Figs. 5, 6 and 7 are diagrammatic views showing the tub and cylinder in cross-section with the cylinder in different positions so as to illustrate the cycle of washing operations taking place in any one of the pockets during a complete revolution of the cylinder.

Referring to Figs. 1 to 4, the washing cylin- 55

der 10 will be seen to be mounted upon horizontal trunnions 11 within the heads 12 of the cylindrical tub 13. The cylinder 10 is divided longitudinally by means of three radially extending partitions 14 into three sector-shaped compartments, and these compartments are further divided by transverse partition walls 15 which are spaced throughout the length of the cylinder so as to provide "Y" pockets 19 of such size as conveniently to handle a batch of wash of suitable proportions. In order to improve the washing action taking place in each of these pockets during a revolution, the cylinder shell is made imperforate but provision is made for the admission of fluid to the pockets through perforated tumbling-ribs 16 extending respectively the full length of the arcuate wall of each pocket and located centrally or nearly centrally with respect to the radial walls thereof. Each tumbling-rib 16 is perforated along both sides as at 17 and 18 to permit ingress and egress of the fluid to the interior of the cylinder with equal facility whether the cylinder be rotating in a clockwise or in an anti-clockwise direction. These ribs 16 will be of the open back type, that is, the cylinder shell will be provided with openings 20 in those portions thereof covered by a rib in order that the tumbling-ribs may act as scoops when passing through the solution in the tub.

To both sides of the radial partitions 14 are secured auxiliary partitions 21 extending between and making tight joints with the transverse partition walls 15. These auxiliary partitions 21 are corrugated, as shown, in such a manner as to form storage pockets 22 distributed along both sides of the radial partitions 14, and communication is provided between storage pockets 22 and "Y" pockets 19 by performing the corrugated partitions 21, as shown at 23. The shape of the auxiliary partitions is such as to offer a scrubbing-board action when the batch or load slides radially along the partitions either toward or away from the center of the cylinder as the latter rotates.

A sliding door is provided for each "Y" pocket and such a sliding door is shown at 24, particular reference being made to Figs. 1 and 3. This door is shaped like the cylinder periphery and is adapted to slide peripherally on the outside of the cylinder in ways 25 formed in a well-known manner adjacent the transverse partitions 15. At its lower or forward edge the door is provided with a plate 27 designed to enter a groove formed at the lower edge of the door opening, so as to provide a secure fit of the door when it is in its closed position. It is to be understood that the details of construction of these features of the door form no essential part of the present invention. It may be noted, however, that along its lower edge the door is provided with an angular rib 28 extending the full length of the door, projecting inwardly from the inner side of the door and then downwardly toward the lower edge thereof. Adjacent the lateral edges of the door and in front of the rib 28 the door shell is cut away to provide openings 29, giving access to pockets 26 formed between the door, the walls of the angular rib 28 and suitable transverse partitions 30—30'. These latter partitions prevent fluid from passing from the interior of the cylinder into the pockets 26 in which are seated certain locking mechanism for holding the door in open and closed position, but which mechanism, forming no part of the invention as set forth in the present application, need not be

specifically described. It will suffice to state that means is provided associated with the said locking mechanism which, as indicated by numeral 31 in Fig. 2, is adapted to extend outwardly from the wall of the cylinder into the path of the door of the tub to prevent closing of the latter except when the cylinder door is locked.

The tub door, indicated at 32, is shaped similarly to the door of the inner cylinder and is guided in lateral ways 33. It is also provided with means, as at 34, for manual operation into open or closed position.

The partitions 30 not only divide the space enclosed by the rib 28 into end pockets for containing the locking mechanism but they also provide a long pocket 35 which may serve as an additional storage pocket for retaining washing fluid. This pocket communicates with the interior of the cylinder by means of a row of perforations 36 distributed along the inner wall of the angular rib, as shown in Figs. 1 and 3. The bottom of pocket 35 is formed by a channel 37 secured between the inner side of the door and the angular rib 28 and having its ends disposed contiguous to partitions 30.

Before describing the operation, it will be well to mention again the fact that the entire interior of the cylinder is divided into a plurality of so-called Y pockets the walls of which are completely imperforate, the only provision for intake and outlet of washing or other cleaning fluid being through the walls of the perforated tumbling-ribs; and that the radial partitions are provided upon both sides with corrugated or scrubbing-boardlike plates which are secured to the said radial partitions and perforated in such a manner as to constitute a plurality of elongated storage pockets, each of which extends from one transverse partition 15 to the next transverse partition 15. These pockets cover each of the partitions 14 substantially from the center of the cylinder to its periphery, forming a plurality of water receptacles adapted in certain positions to receive the washing fluid and in other positions to discharge the fluid in a spray upon the goods contained in the respective pocket. It is further to be noted that the angular ribs 28 provided along the bottom edges of each door to reinforce the door and to provide watertight compartments for the locking mechanism, serve also to provide long storage pockets in addition to the storage pockets formed upon the radial partitions.

By reference to Figs. 5, 6 and 7, and following a cycle of operations as illustrated by the letters A to I, a clear conception may be had of what takes place in the several Y pockets during a complete revolution of the cylinder. In these figures the direction of rotation is indicated by 60 the arrows. The storage pockets on the advancing sides of the radial partitions may be called "leading" pockets and those on the other side of said partitions "following" pockets. At A in Fig. 5 may be seen a batch of wash as it is advanced 65 by a tumbling-rib. In this position the batch will have a tendency to valve off tumbling-rib perforations upon the left side of the tumbling-rib while water will be freely admitted through perforations in the right side thereof. As the 70 cylinder rotates this same compartment will next be in a position similar to B in Fig. 7. Here it will be noted that the batch or a portion thereof has been lifted clear of the fluid and that the tumbling-rib is about to emerge from the water. 75

contained in the tub, after which no more water can enter the pocket. As the pocket passes from position B to position C in Fig. 6, the lifted material will be effectively squeezed by gravity action before it falls over the inner edge of the tumbling-rib. In position C the solution will stand in the corner formed between the periphery of the pocket and the rearward radial partition and into the solution the lifted portion of the batch of material will fall and be more or less tightly compacted to occasion a further squeezing of the material.

From position C through position D to E the batch will lie in the solution and become more loosely distributed or spread out along the radial partition. At the same time the solution will start to flow along the radial partition toward the center of the cylinder until, in position E, all of the "leading" pockets will be flooded. Now, as a Y pocket rotates with the cylinder successively to positions G and H, the clothes will slide at first along the exterior of the "leading" pockets and then along the exterior of the "following" pockets belonging to such Y pocket with a scrubbing action, and then again become partially submerged in the surplus fluid which will have collected in the then lower corner of the Y pocket. At about the time position H is reached the batch will receive a drenching of fluid sprayed from the "leading" storage pockets extending along the rearward or, in this position, the upper partition of the Y pocket.

In position I the load will be in a position, as the Y pocket is again submerged, to valve off the left side of the tumbling-rib, preventing egress of fluid from the pocket, but not preventing the subsequent ingress of fluid through the perforations in the right side of the tumbling-rib as the latter passes again to positions A and B. It will be noted, also, that as a Y pocket turns from the position shown in H to that shown in I, fluid contained therein will flow to the tumbling-rib and pass outwardly into the tub through the perforations located in the advancing side of said rib. As during the passage of a Y pocket from position E to position F the "following" storage pockets will be filled with solution, it follows that while that pocket moves from position H, through I and A to B, fluid from the "following" pockets will be emptied upon the batch of wash. Thus the batch will be twice sprayed during each revolution.

It should be noted that the washing fluid never passes directly from one Y pocket to another, but is cyclicly taken from and again discharged into the tub. This insures that all lint or accumulations of dirt will be discharged into the tub and finally disposed of when the tub is emptied.

The perforated corrugated auxiliary partitions, besides forming scrubbing surfaces and storage pockets, also serve effectively to increase the strength and rigidity of the radial partitions of the cylinder and as they are easily riveted at points between the corrugations to the radial partitions, as indicated at 42, the construction is simple and convenient to make. All the parts coming in contact with the washing fluid are preferably made of a non-corrosive metal such as Monel and any suitable means may be provided for producing either continuous or reversed rotation of the cylinder within the tub.

In Figs. 1 and 2 tub standards are indicated, as at 38, and a central dump opening is shown at 39 for the discharge of the used washing so-

lution from the tub. Fresh solution may be admitted through the conduit 40. Any suitable dump-valve may be employed such as the lift-valve 41 shown in Fig. 2.

It will be seen that there is provided a construction of an essentially practical nature in which the several objects of this invention are attained.

As many possible embodiments may be made of the above invention without departing from the scope thereof, it is to be understood that all matter herein set forth or shown in the accompanying drawings is to be interpreted as illustrative and not in a limiting sense.

I claim:

1. In a machine of the class described, in combination, an outer tub for treating fluid, a cylinder rotatably mounted in said tub, means comprising a pair of spaced imperforate partitions radiating from the axial center to the periphery of said cylinder for forming a load-carrying pocket therein, the cylinder wall lying between the outer edges of said partitions being imperforate except a portion thereof medially disposed with respect to said partitions, which portion is provided with openings extending through said wall, and means for intermittently trapping fluid from circulation within said pocket and releasing it for circulation within said pocket.

2. In a machine of the class described, in combination, an outer tub for treating fluid, a cylinder rotatably mounted in said tub, means comprising a pair of spaced imperforate partitions radiating from the axial center to the periphery of said cylinder for forming a load-carrying pocket therein, the cylinder wall lying between the outer edges of said partitions being imperforate except a portion thereof medially disposed with respect to said partitions, which portion is provided with openings extending through said wall, and means on said radial partitions for receiving and withholding fluid from the interior of said pocket during a period of revolution of said cylinder and returning said fluid to said pocket during a later period of revolution.

3. In a machine of the class described, in combination, an outer tub for a treating fluid, a cylinder rotatably mounted in said tub, means comprising a pair of imperforate radial partitions within said cylinder for forming a sector-shaped pocket therein, an opening in the peripheral wall of said pocket disposed substantially centrally with respect to said radial partitions, said peripheral wall being otherwise imperforate, a perforated tumbling-rib covering said opening and projecting within said pocket, and a plurality of fluid storage receptacles mounted on said radial partitions and opening into said pocket adapted to become filled with fluid flowing over said imperforate partitions during rotation of said cylinder and then to be emptied at a later period during rotation of said cylinder.

4. In a machine of the class described, in combination, an outer tub for a treating fluid, a cylinder rotatably mounted in said tub, means comprising a pair of imperforate radial partitions within said cylinder for forming a sector-shaped pocket therein, an opening in the peripheral wall of said pocket disposed substantially centrally with respect to said radial partitions, said peripheral wall being otherwise imperforate, a perforated tumbling-rib covering said opening and projecting within said pocket, a plurality of fluid storage receptacles mounted on said radial

- partitions in said pocket, an imperforate door slidably mounted upon said cylinder and adapted to give access to said pocket, a fluid storage receptacle on said door providing additional storage space for fluid, and means connecting the interiors of all of said storage receptacles with the interior of said sector-shaped pocket whereby said storage receptacles are adapted successively to receive fluid from said sector-shaped pocket as the cylinder rotates and then to return said fluid to the interior of the same sector-shaped pocket as a spray.
5. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a plurality of fluid receptacles presenting scrubbing surfaces within each pocket, and means for admitting treating fluid from said tub to the interior of said sector-shaped pockets.
10. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a plurality of fluid receptacles presenting scrubbing surfaces within each pocket, and means for admitting treating fluid from said tub to the interior of said sector-shaped pockets.
15. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a series of storage receptacles having scrubbing surfaces within each pocket, and means for admitting fluid from said tub to the interior of said pockets.
20. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a plurality of fluid receptacles presenting scrubbing surfaces within each pocket, and means for admitting fluid from said tub to the interior of said pockets.
25. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a series of storage receptacles having scrubbing surfaces within each pocket, and means for admitting fluid from said tub to the interior of said pockets.
30. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a plurality of fluid receptacles presenting scrubbing surfaces within each pocket, and means for admitting fluid from said tub to the interior of said pockets.
35. In a machine of the class described, in combination, an outer tub for a treating fluid, a cylinder rotatably mounted in said tub, means comprising imperforate radial partitions within said cylinder for forming a plurality of sector-shaped pockets therein, means comprising perforated corrugated sheets secured to said partitions to provide a series of storage receptacles having scrubbing surfaces within each pocket, and means for admitting fluid from said tub to the interior of said pockets.
40. 7. In a washing machine, in combination, a tub for washing fluid, a cylindrical load container rotatably mounted in said tub and having radially extending imperforate partitions mounted therein for dividing said container into compartments, one of said partitions being provided with a plurality of longitudinally extending receptacles communicating with one of said compartments and adapted to lift fluid contained in said one compartment and discharge the same upon the load being washed in the same compartment.
45. 8. In a washing machine, in combination, a tub for washing fluid, a cylindrical load container rotatably mounted in said tub and having radially extending imperforate partitions mounted therein for dividing said container into compartments, each of said partitions being provided with
- a plurality of longitudinally extending receptacles communicating with one of said compartments and adapted to lift fluid contained in said one compartment and discharge the same upon the load being washed in the same compartment.
5. In a washing machine, in combination, a tub for washing fluid, an imperforate cylindrical load container rotatably mounted in said tub and having radially extending imperforate partitions mounted therein for dividing said container into compartments, said partitions being provided with longitudinally extending pockets adapted to lift fluid contained in said compartments and discharge the same upon the load being washed in said compartments, and perforated baffles located substantially centrally of the peripheral walls of said compartments in registry with openings in said peripheral walls for inducing the passage of fluid contained in said tub to and from said compartments.
10. In a machine of the class described, in combination, an outer tub for a treating fluid, a cylinder rotatably mounted in said tub, means comprising imperforate radial partitions within said cylinder forming a plurality of sector-shaped pockets therein, means comprising perforated corrugated sheets secured to said partitions to provide a series of storage receptacles having scrubbing surfaces within each pocket, and means for admitting fluid from said tub to the interior of said pockets.
15. In a machine of the class described, in combination, an outer tub for a treating fluid, a cylinder rotatably mounted in said tub, means comprising a pair of spaced imperforate partitions radiating from the axial center to the periphery of said cylinder for forming a load-carrying pocket therein, and means on said radial partitions for receiving and withholding fluid from the interior of said pocket during a period of revolution of said cylinder and returning said fluid to said pocket during a later period of revolution.
20. 11. In a machine of the class described, in combination, an outer tub for treating fluid, a cylinder rotatably mounted in said tub, means comprising a pair of spaced partitions radiating from the axial center to the periphery of said cylinder for forming a load-carrying pocket therein, and means on said radial partitions for receiving and withholding fluid from the interior of said pocket during a period of revolution of said cylinder and returning said fluid to said pocket during a later period of revolution.
25. 12. In a machine of the class described, in combination, an outer tub for treating fluid, a cylinder rotatably mounted in said tub, means comprising a pair of spaced partitions radiating from the axial center to the periphery of said cylinder for forming a load-carrying pocket therein, and means mounted upon one of said partitions and forming with an imperforate portion of said one partition a storage chamber adapted to receive and withhold fluid from the interior of said pocket during a period of revolution of the cylinder and to return said fluid to said pocket during a later period of revolution.
30. WILLIAM STROBRIDGE.
